UNITED STATES PATENT OFFICE.

JOSEPH W. BRAGSTAD, OF SIOUX CITY, IOWA.

REINFORCED CONCRETE CONSTRUCTION.

1,107,486.

Specification of Letters Patent. Patented Aug. 18, 1914.

Application filed October 21, 1913. Serial No. 796,476.

To all whom it may concern:

Be it known that I, JOSEPH W. BRAGSTAD, a citizen of the United States, and a resident of Sioux City, in the county of Woodbury and State of Iowa, have invented certain new and useful Improvements in Reinforced Concrete Construction, of which the following is a specification.

This invention relates to reinforced concrete construction.

The primary object of the invention is the production of an improved concrete construction stable and durable and wherein the cost of construction is reduced to the minimum.

Another object is the production of improved sheet-metal plates which serve both as form and reinforcing members.

With the above and other objects in view, the invention, consisting in the construction, combination and novel arrangement of parts, will be fully understood from the following description, reference being had to the accompanying drawings which form a part of this application and in which like characters of reference indicate corresponding parts throughout the several views, of which,—

Figure 1 is a fragmentary horizontal section of a wall constructed in accordance with my invention; Fig. 2 is a vertical section of a modified form of wall suitable as a retaining wall or other structure wherein great strength is required; Fig. 3 is a fragmentary side elevation of the reinforcement plates employed in the modification; Fig. 4 is a fragmentary side elevation of the reinforcing plates presented in Fig. 1; Fig. 5 is a vertical section taken on the line *a*—*b* of Fig. 4 in the direction indicated by the arrows; Fig. 6 is a detail perspective view of the reinforcement plates; and Fig. 7 is a perspective view of the hollow wall construction.

The invention contemplates a concrete construction wherein the reinforcing members comprise outer and inner sheet-metal plates maintained in parallel and spaced relation to each other by means of transverse ties, and adapted to serve as a mold for the reception of concrete, and upon the outer faces of which plaster or stucco may be applied.

The invention may be either applied to monolithic or hollow wall construction. In the latter application a continuous dead-air

space may be provided by constructing two of the above-described walls in suitable spaced relation to each other, and, if desired, the two walls may be interconnected, at intervals, by transverse ties.

Referring now to the illustrations, the outer and inner reinforcement or form members are each comprised of separate sheet-metal plates, 6, the upper edges of which are bent outwardly at an angle from the plates thus forming wings, 7, which are provided with longitudinal slots, 8; and the lower edges of which are bent at an angle inwardly forming wings, 9, oppositely-disposed to the wings, 7. Portions of the wings, 9, aligned with the slots, 8, are sheared and bent outwardly forming tenons, 10. In assembling the plates the slots, 8, admit the tenons of the plates immediately above, and the outwardly-angled edges of the plates embrace the inwardly-angled edges of the adjacent plates, as clearly shown in Figs. 2 and 7. When employed in monolithic construction, where great strength is essential, the plates are held in parallelism and lateral displacement thereof is prevented by suitable ties, such as the rods, 11, the ends of which are passed outwardly through apertures, 12, then bent inwardly through apertures, 13, and the extreme ends bent over adjacent the inner faces of the plates. When the invention is applied in hollow wall construction, the separate plates are assembled in the manner previously set forth; however, in order to simplify the process of construction and obviate the expense of additional material for interconnecting the outer and inner shells, longitudinal strips, 14, are punched from the plates and bent laterally toward the opposite plates. The free ends of the punchings are reduced affording shoulders, 15, which engage the opposite plates, the reduced portions being extended through slots, 16, and the protruding ends bent laterally adjacent the outer face of the plates. The punchings are disposed in horizontal rows which are alternately arranged with respect to the rows of the opposite plates. In either monolithic or hollow wall construction the plates are arranged in courses and concrete, 17, then filled in between them. During the process of filling, portions of the wet concrete will protrude through the slots and other apertures of the plates and this may be troweled up on the outer faces of the plates.

Stucco or cement, 18, is applied to the outer faces of the plates, and the punchings are covered with stucco or cement, 19, which is applied in horizontal rows, the rows being alternately arranged with respect to the rows of the punchings. The punchings are then covered with stucco or cement, 20, which is applied in horizontal rows, the rows being alternately arranged with respect to the rows of the punchings. The punchings are then covered with stucco or cement, 21, which is applied in horizontal rows, the rows being alternately arranged with respect to the rows of the punchings. The punchings are then covered with stucco or cement, 22, which is applied in horizontal rows, the rows being alternately arranged with respect to the rows of the punchings. The punchings are then covered with stucco or cement, 23, which is applied in horizontal rows, the rows being alternately arranged with respect to the rows of the punchings. The punchings are then covered with stucco or cement, 24, which is applied in horizontal rows, the rows being alternately arranged with respect to the rows of the punchings. The punchings are then covered with stucco or cement, 25, which is applied in horizontal rows, the rows being alternately arranged with respect to the rows of the punchings. The punchings are then covered with stucco or cement, 26, which is applied in horizontal rows, the rows being alternately arranged with respect to the rows of the punchings. The punchings are then covered with stucco or cement, 27, which is applied in horizontal rows, the rows being alternately arranged with respect to the rows of the punchings. The punchings are then covered with stucco or cement, 28, which is applied in horizontal rows, the rows being alternately arranged with respect to the rows of the punchings. The punchings are then covered with stucco or cement, 29, which is applied in horizontal rows, the rows being alternately arranged with respect to the rows of the punchings. The punchings are then covered with stucco or cement, 30, which is applied in horizontal rows, the rows being alternately arranged with respect to the rows of the punchings. The punchings are then covered with stucco or cement, 31, which is applied in horizontal rows, the rows being alternately arranged with respect to the rows of the punchings. The punchings are then covered with stucco or cement, 32, which is applied in horizontal rows, the rows being alternately arranged with respect to the rows of the punchings. The punchings are then covered with stucco or cement, 33, which is applied in horizontal rows, the rows being alternately arranged with respect to the rows of the punchings. The punchings are then covered with stucco or cement, 34, which is applied in horizontal rows, the rows being alternately arranged with respect to the rows of the punchings. The punchings are then covered with stucco or cement, 35, which is applied in horizontal rows, the rows being alternately arranged with respect to the rows of the punchings. The punchings are then covered with stucco or cement, 36, which is applied in horizontal rows, the rows being alternately arranged with respect to the rows of the punchings. The punchings are then covered with stucco or cement, 37, which is applied in horizontal rows, the rows being alternately arranged with respect to the rows of the punchings. The punchings are then covered with stucco or cement, 38, which is applied in horizontal rows, the rows being alternately arranged with respect to the rows of the punchings. The punchings are then covered with stucco or cement, 39, which is applied in horizontal rows, the rows being alternately arranged with respect to the rows of the punchings. The punchings are then covered with stucco or cement, 40, which is applied in horizontal rows, the rows being alternately arranged with respect to the rows of the punchings. The punchings are then covered with stucco or cement, 41, which is applied in horizontal rows, the rows being alternately arranged with respect to the rows of the punchings. The punchings are then covered with stucco or cement, 42, which is applied in horizontal rows, the rows being alternately arranged with respect to the rows of the punchings. The punchings are then covered with stucco or cement, 43, which is applied in horizontal rows, the rows being alternately arranged with respect to the rows of the punchings. The punchings are then covered with stucco or cement, 44, which is applied in horizontal rows, the rows being alternately arranged with respect to the rows of the punchings. The punchings are then covered with stucco or cement, 45, which is applied in horizontal rows, the rows being alternately arranged with respect to the rows of the punchings. The punchings are then covered with stucco or cement, 46, which is applied in horizontal rows, the rows being alternately arranged with respect to the rows of the punchings. The punchings are then covered with stucco or cement, 47, which is applied in horizontal rows, the rows being alternately arranged with respect to the rows of the punchings. The punchings are then covered with stucco or cement, 48, which is applied in horizontal rows, the rows being alternately arranged with respect to the rows of the punchings. The punchings are then covered with stucco or cement, 49, which is applied in horizontal rows, the rows being alternately arranged with respect to the rows of the punchings. The punchings are then covered with stucco or cement, 50, which is applied in horizontal rows, the rows being alternately arranged with respect to the rows of the punchings. The punchings are then covered with stucco or cement, 51, which is applied in horizontal rows, the rows being alternately arranged with respect to the rows of the punchings. The punchings are then covered with stucco or cement, 52, which is applied in horizontal rows, the rows being alternately arranged with respect to the rows of the punchings. The punchings are then covered with stucco or cement, 53, which is applied in horizontal rows, the rows being alternately arranged with respect to the rows of the punchings. The punchings are then covered with stucco or cement, 54, which is applied in horizontal rows, the rows being alternately arranged with respect to the rows of the punchings. The punchings are then covered with stucco or cement, 55, which is applied in horizontal rows, the rows being alternately arranged with respect to the rows of the punchings. The punchings are then covered with stucco or cement, 56, which is applied in horizontal rows, the rows being alternately arranged with respect to the rows of the punchings. The punchings are then covered with stucco or cement, 57, which is applied in horizontal rows, the rows being alternately arranged with respect to the rows of the punchings. The punchings are then covered with stucco or cement, 58, which is applied in horizontal rows, the rows being alternately arranged with respect to the rows of the punchings. The punchings are then covered with stucco or cement, 59, which is applied in horizontal rows, the rows being alternately arranged with respect to the rows of the punchings. The punchings are then covered with stucco or cement, 60, which is applied in horizontal rows, the rows being alternately arranged with respect to the rows of the punchings. The punchings are then covered with stucco or cement, 61, which is applied in horizontal rows, the rows being alternately arranged with respect to the rows of the punchings. The punchings are then covered with stucco or cement, 62, which is applied in horizontal rows, the rows being alternately arranged with respect to the rows of the punchings. The punchings are then covered with stucco or cement, 63, which is applied in horizontal rows, the rows being alternately arranged with respect to the rows of the punchings. The punchings are then covered with stucco or cement, 64, which is applied in horizontal rows, the rows being alternately arranged with respect to the rows of the punchings. The punchings are then covered with stucco or cement, 65, which is applied in horizontal rows, the rows being alternately arranged with respect to the rows of the punchings. The punchings are then covered with stucco or cement, 66, which is applied in horizontal rows, the rows being alternately arranged with respect to the rows of the punchings. The punchings are then covered with stucco or cement, 67, which is applied in horizontal rows, the rows being alternately arranged with respect to the rows of the punchings. The punchings are then covered with stucco or cement, 68, which is applied in horizontal rows, the rows being alternately arranged with respect to the rows of the punchings. The punchings are then covered with stucco or cement, 69, which is applied in horizontal rows, the rows being alternately arranged with respect to the rows of the punchings. The punchings are then covered with stucco or cement, 70, which is applied in horizontal rows, the rows being alternately arranged with respect to the rows of the punchings. The punchings are then covered with stucco or cement, 71, which is applied in horizontal rows, the rows being alternately arranged with respect to the rows of the punchings. The punchings are then covered with stucco or cement, 72, which is applied in horizontal rows, the rows being alternately arranged with respect to the rows of the punchings. The punchings are then covered with stucco or cement, 73, which is applied in horizontal rows, the rows being alternately arranged with respect to the rows of the punchings. The punchings are then covered with stucco or cement, 74, which is applied in horizontal rows, the rows being alternately arranged with respect to the rows of the punchings. The punchings are then covered with stucco or cement, 75, which is applied in horizontal rows, the rows being alternately arranged with respect to the rows of the punchings. The punchings are then covered with stucco or cement, 76, which is applied in horizontal rows, the rows being alternately arranged with respect to the rows of the punchings. The punchings are then covered with stucco or cement, 77, which is applied in horizontal rows, the rows being alternately arranged with respect to the rows of the punchings. The punchings are then covered with stucco or cement, 78, which is applied in horizontal rows, the rows being alternately arranged with respect to the rows of the punchings. The punchings are then covered with stucco or cement, 79, which is applied in horizontal rows, the rows being alternately arranged with respect to the rows of the punchings. The punchings are then covered with stucco or cement, 80, which is applied in horizontal rows, the rows being alternately arranged with respect to the rows of the punchings. The punchings are then covered with stucco or cement, 81, which is applied in horizontal rows, the rows being alternately arranged with respect to the rows of the punchings. The punchings are then covered with stucco or cement, 82, which is applied in horizontal rows, the rows being alternately arranged with respect to the rows of the punchings. The punchings are then covered with stucco or cement, 83, which is applied in horizontal rows, the rows being alternately arranged with respect to the rows of the punchings. The punchings are then covered with stucco or cement, 84, which is applied in horizontal rows, the rows being alternately arranged with respect to the rows of the punchings. The punchings are then covered with stucco or cement, 85, which is applied in horizontal rows, the rows being alternately arranged with respect to the rows of the punchings. The punchings are then covered with stucco or cement, 86, which is applied in horizontal rows, the rows being alternately arranged with respect to the rows of the punchings. The punchings are then covered with stucco or cement, 87, which is applied in horizontal rows, the rows being alternately arranged with respect to the rows of the punchings. The punchings are then covered with stucco or cement, 88, which is applied in horizontal rows, the rows being alternately arranged with respect to the rows of the punchings. The punchings are then covered with stucco or cement, 89, which is applied in horizontal rows, the rows being alternately arranged with respect to the rows of the punchings. The punchings are then covered with stucco or cement, 90, which is applied in horizontal rows, the rows being alternately arranged with respect to the rows of the punchings. The punchings are then covered with stucco or cement, 91, which is applied in horizontal rows, the rows being alternately arranged with respect to the rows of the punchings. The punchings are then covered with stucco or cement, 92, which is applied in horizontal rows, the rows being alternately arranged with respect to the rows of the punchings. The punchings are then covered with stucco or cement, 93, which is applied in horizontal rows, the rows being alternately arranged with respect to the rows of the punchings. The punchings are then covered with stucco or cement, 94, which is applied in horizontal rows, the rows being alternately arranged with respect to the rows of the punchings. The punchings are then covered with stucco or cement, 95, which is applied in horizontal rows, the rows being alternately arranged with respect to the rows of the punchings. The punchings are then covered with stucco or cement, 96, which is applied in horizontal rows, the rows being alternately arranged with respect to the rows of the punchings. The punchings are then covered with stucco or cement, 97, which is applied in horizontal rows, the rows being alternately arranged with respect to the rows of the punchings. The punchings are then covered with stucco or cement, 98, which is applied in horizontal rows, the rows being alternately arranged with respect to the rows of the punchings. The punchings are then covered with stucco or cement, 99, which is applied in horizontal rows, the rows being alternately arranged with respect to the rows of the punchings. The punchings are then covered with stucco or cement, 100, which is applied in horizontal rows, the rows being alternately arranged with respect to the rows of the punchings. The punchings are then covered with stucco or cement, 101, which is applied in horizontal rows, the rows being alternately arranged with respect to the rows of the punchings. The punchings are then covered with stucco or cement, 102, which is applied in horizontal rows, the rows being alternately arranged with respect to the rows of the punchings. The punchings are then covered with stucco or cement, 103, which is applied in horizontal rows, the rows being alternately arranged with respect to the rows of the punchings. The punchings are then covered with stucco or cement, 104, which is applied in horizontal rows, the rows being alternately arranged with respect to the rows of the punchings. The punchings are then covered with stucco or cement, 105, which is applied in horizontal rows, the rows being alternately arranged with respect to the rows of the punchings. The punchings are then covered with stucco or cement, 106, which is applied in horizontal rows, the rows being alternately arranged with respect to the rows of the punchings. The punchings are then covered with stucco or cement, 107, which is applied in horizontal rows, the rows being alternately arranged with respect to the rows of the punchings. The punchings are then covered with stucco or cement, 108, which is applied in horizontal rows, the rows being alternately arranged with respect to the rows of the punchings. The punchings are then covered with stucco or cement, 109, which is applied in horizontal rows, the rows being alternately arranged with respect to the rows of the punchings. The punchings are then covered with stucco or cement, 110, which is applied in horizontal rows, the rows being alternately arranged with respect to the rows of the punchings.

18, may then be applied to the outer faces of the wall. In hollow wall construction the outer and inner walls, 19 and 20, respectively, (Figs. 1 and 7) are constructed in spaced relation with each other and interconnected by any suitable cross-members, as the bars, 21, which are, obviously, placed in position as the forms are erected.

In Fig. 1 an upright timber, 22, extends into the air-space intermediate the outer and inner walls, to which member is secured a window frame, 23, provided with the usual casing, 24; stops, 25; sash, 26; sill, 27; and blind-stop, 28, which abuts the edge of the outer wall. The spaces intermediate the upright 22 and the inner faces of the walls; and the frame 23 and the edges of the walls, are filled with concrete, 17, whereby an airtight connection between the casing and window is obtained.

Having thus described my invention, what I claim as new and desire to secure by Letters Patent, is,—

1. In reinforced concrete construction, outer and inner reinforcement and form members, each comprising separate plates assembled one above the other and each having upper portions provided with slots and formed at an angle to the plate; lower portions formed at an angle to the plate and oppositely to the upper angled portions; tenons sheared from the lower portions and positioned to be received by the slots of the adjacent plate; and cross-members interconnecting said outer and inner reinforcement and form members.

2. In reinforced concrete construction, outer and inner reinforcement and form

members, each comprising separate integral plates assembled one above the other and provided with apertures and each plate having upper portions provided with slots and formed at an angle to the plate; lower portions formed at an angle to the plate and oppositely to the upper angled portions; tenons sheared from the lower portions and positioned to be received by the slots of the adjacent plate; elongated intermediate portions punched from the plate and bent toward the opposite plate, said elongated portions having free ends reduced and adapted to be engaged within the apertures of the opposite plate.

3. In reinforced concrete construction, outer and inner reinforcement and form members, each comprising separate sheet-metal plates assembled in a vertical plane, edge to edge, and each plate having elongated portions punched from and bent laterally toward the opposite plate, said plates being provided with apertures intermediate the elongated members and adapted to receive the free ends of the elongated portions of the opposite plates, said free ends being reduced to afford shoulders to engage the inner faces of and prevent the plates from displacement toward each other; and means for interlocking the edges of each plate with those immediately adjacent.

In testimony whereof I have hereunto set my hand in the presence of two subscribing witnesses.

JOSEPH W. BRAGSTAD.
